Primary Examiner — Jonathan J Han*Assistant Examiner* — Molly K. Orzechowski(74) *Attorney, Agent, or Firm* — Banner & Witcoff, Ltd.(57) **CLAIM**

The ornamental design for a shoe as shown and described.

DESCRIPTION

FIG. 1 is a front perspective view of a shoe showing my new design;

FIG. 2 is a side view thereof;

FIG. 3 is a rear perspective view thereof;

FIG. 4 is a rear view thereof;

FIG. 5 is an opposite side rear perspective view thereof;

FIG. 6 is an opposite side view thereof;

FIG. 7 is an opposite side front perspective view thereof; and,

FIG. 8 is a front view thereof.

The broken lines immediately adjacent to portions of the shaded area represent grooves on the bottom of the shoe and form no part of the claimed design. The broken lines depicting the remainder of the shoe form no part of the claimed design.

1 Claim, 8 Drawing Sheets(56)
